 2 Claims. (Cl. 24—207)

This invention relates to fasteners used for joining together edges of webs of materials. The invention refers more particularly to fasteners which are adapted to join together webs of materials in an air-tight, water-tight and dust-tight relationship.

The joining together of webs by means of fastener elements which are opened and closed by a slide fastener is well known. Fasteners are also known which are provided with spaced fastening clamps, these clamps being drawn over beaded upstanding edges of two webs so that these two webs are held together at suitably spaced points. Constructions of both types of these fasteners are known which tend to resist penetration by air, water and dust.

An object of the present invention is to improve these prior art constructions through the provision of a fastener which establishes a tight seal between the webs.

Other objects of the present invention will become apparent in the course of the following specification.

In the accomplishment of the objectives of the present invention it was found desirable to provide a fastener of the type wherein fastening clamps are drawn over beaded edges of the webs and are joined by means of a slider.

In order that the invention may be more clearly understood, reference will now be made to the accompanying drawings, in which:

FIGURE 1 is a section on the line I—I of FIGURE 3,
 FIGURE 2 is a section on the line II—II of FIGURE 3,
 FIGURE 3 shows a side view of a sliding clasp fastener with the slider sectioned approximately in the middle.

FIGURE 4 is a bottom plan view of the slider shown in FIG. 3 looking in the direction of the arrow H shown in FIG. 3.

Two tapes 1 of rubber or similar material, which are produced by injection moulding or die pressing are lined with inextensible tapes 2 in order to prevent stretching. Members 3 grip the beading shown at 4 and 5, and are thus firmly fixed on the tapes 1.

The slide members 3 are clamped together by clamps 6. Claws 6₁ (see FIGURES 1 and 2) on the clamps 6 hold the clamps 6 so that they cannot lift off or slide upwards.

If the tapes 1 are stretched and pulled apart, i.e. to the right and left as shown in FIGURES 1 and 2, the members 3 are tipped closer to the claws 6₁, in a somewhat downward direction over the claws. Sealing lips 9₁ on the tapes 1 are thus pushed together and the seal of the sliding clasp fastener is thereby increased. This is an important feature of the invention.

The clamps 6 are held at suitable distances along and on the tape 2, as shown in FIGURE 3, by means of the beading 8.

When the sliding clasp fastener is closed and opened by means of the slider 7, as shown in FIGURES 1 to 3, the members 3 are somewhat pressed together by inwardly pointing hook portions 7₂ (FIGURE 2). The hook portions 7₂ pass into the positions 7₃, acting in the manner of wedges. This position is also shown by the reference numeral 7₃ in FIGURE 3. This pressing together releases the hook portions 6₁ and the clamps 6 are thus able to move without hindrance. Sloping rails 7₁ on the slider 7 push the clamps 6 upwards or downwarls. When the hook portions 7₂ leave the members 3 and the clamps 6 are in the raised position, the tapes 1 are no longer clamped and the sliding clasp fastener is open.

2

There is no need of a wedge-strut such as is provided in most types of sliding clasp fastener.

In FIGURES 1 and 2 the left hand tape 2 has a bent portion 8₁. In order to ensure that this bend is reliably effected at this point the perforations 8₂ shown in FIGURE 2 are provided. When the tape 2 consists of fibreless plastics material the perforations 8₂ are preferably latticed.

The free spaces 9 in the tapes 1 (FIGURES 1 and 2) facilitate the passage of the hook portions 7₂ into the positions 7₃, which has already been mentioned.

The sliding clasp fastener according to the present invention has the advantage of simplicity and inexpensiveness when compared with sliding clasp fasteners resisting penetration of air, water and dust as hitherto known. It has, however, another special advantage. All types of sliding clasp fasteners with inter-engaging fastener elements open throughout their length if only one member is damaged and is thus disengaged. The sliding clasp fastener according to the present invention does not open when the closing seam is damaged in one or more places.

The clasp fastener of the present invention is opened and closed in the following manner:

When the fastener is in the sealed position shown in FIG. 1, and the member 7 is moved over it (for example

25 in the direction toward the left in FIG. 3) the portions 7₃ will press the members 3 inwardly sufficiently so that the claws 6₁ of the clamping member 6 are no longer retained by the members 3. As the member 7 is moved along the fastener, the individual short clamp members 6 will be raised by the inclined track 7₁ out of the plane in which the claws 6₂ could reengage the recesses in members 3. Then the fastener assumes the position shown in FIG. 2. Then the slide member 6 is no longer clamping the members 3 together and the two webs can be separated. In the 30 illustrated construction the clamp member 6 is still attached to the left hand web member by means of the tape 8 and thus it cannot become loose.

The webs 1 are provided with spaces 9 at their common edge 9. These spaces aid in permitting the inward deformation of the web members so that the portions 7₃ of the slider can press the members 3 inwardly in the manner which has just been described.

40 In FIGURE 3 it can be seen that the closure tapes 1 are also held together in a sealed manner along the sectioned line II—II through the portion 7₂ of the slider. The stresses of the tape 1 pulling them to the left or right cause the members 3 to tip about the rounded portion 7₂ so that the sealing lips are pressed closer together at 9₁. At the left hand side of FIGURE 1 is shown a portion 10. 45 When the clamps 6 are made of inexpensive flexible material, the portions 10, operating in the manner of wedges, push the opened clamps 6 together in the lower position. In inexpensive sliding clasp fasteners of this type it is unnecessary for the clamps 6 to be connected to the tape 2 by means of the portions 8 of said tape. The portion 8 may be a separate tape which is independently inserted in the slider and carries the opened clamps 6.

50 What I claim is:

- 60 1. A clasp fastener for joining two webs at abutting edges thereof comprising:
 (a) an upstanding portion on each of said two abutting edges, said two upstanding portions being in facing relationship and being adapted to mate sealingly together;
 (b) at least one outer member secured to each of said upstanding portions on the side thereof remote from said other upstanding portion, said outer member having a recess, and
 (c) a plurality of clamping members adapted to fit over said abutting edges and said outer members adapted to clamp said webs together, said clamping

- members being spaced along the length of said fastener;
- (d) said clamping members being joined to one another by a flexible connecting member, said flexible connecting member also being connected to one of said webs;
- (e) said clamping members also having claws adapted to fit into said recesses to retain said clamping member in clamping position.
2. A clasp fastener as described in claim 1 including a slider member in which each outer member is provided adjacent its bottom with a groove adapted to guide said slider member, said grooves being so positioned that pressure exerted by said slider member therein will cause

movement of said outer members towards one another and consequent release of said claws from said recesses.
